FLUID SENSITIVE DETONATOR ASSEMBLY
Ernest L. Gillingham, Fort Worth, and Jack O. Grunwald,
Arlington, Tex., assignors to Jet Research Center, Inc.,
Arlington, Tex., a corporation of Texas
Filed July 14, 1960, Ser. No. 42,785
5 Claims. (Cl. 102—20)

The present invention relates to a detonator assembly for an explosive device. More particularly, the invention relates to a fluid sensitive detonator assembly for firing a detonating fuse in a well perforating apparatus, and to the well perforating apparatus including such detonator.

The conventional method of detonating shaped charge units in a well perforating apparatus is to use a length of detonating fuse, such as "Primacord," manufactured by The Ensign-Bickford Co. Normally, an electric blasting cap is used to initiate the detonating fuse. The shaped charge units are often mounted in an elongated, hollow, cylindrical, liquid-tight carrier for disposition in the well borehole. It is essential that the carrier remain free of liquids until the shaped charges are detonated. Should liquid enter the carrier and cover the shaped charges, the jets will not form properly when the charges are detonated and little or no perforation of the well casing and earth formation will occur. Also, the presence of liquid in a hollow, heavy walled, reusable type carrier will not allow sufficient expansion of the gases produced by the detonating charge units with resultant distortion damage to the carrier.

To overcome these objectionable effects, detonating devices have been developed which are rendered inactive by the presence of liquids in a hollow carrier. Such a detonating device is disclosed in U.S Patent No 2,891,477, issued June 23, 1959, to Merrill E. Swanson and entitled "Initiation Device Desensitized by Fluids." The apparatus of the present invention is an improvement upon the device disclosed therein. Detonating devices, such as disclosed in the aforementioned patent, are usually located in the bottom of a hollow carrier for ready deactivation upon ingress of even a small amount of fluid from the well bore into the hollow space of the carrier.

The shaped charges and a length of detonating fuse, in detonating relationship to the shaped charges, are usually placed in the carrier before it is delivered to the well. For safety reasons, the detonating device is attached to the detonating fuse immediately before the perforating apparatus is run into the well bore. An electric blasting cap is crimped to the lower end of the detonating fuse which extends to the open lower end of the hollow carrier. Electrical connections are made which permit firing of the blasting cap from the earth's surface. The blasting cap, with its attached detonating fuse and electrical lead wires, must be pushed back up into the end of the carrier to permit the open end to be closed with a bulb nose, or other suitable closing member. This operation may cause a sharp bend to occur in the detonating fuse because of the excessive length of fuse confined in the narrow space at the end of the hollow carrier. A sharp bend in a detonating fuse will often cause the fuse to part at the point of the bend when the fuse is detonated. Thus, the fuse does not detonate over its entire length and fails to fire the shaped charge perforating units. When this type of misfire occurs, the perforating apparatus must be retrieved to the earth's surface and a spare perforating apparatus run into the well. Normally, a misfire of this nature will not leave a sufficient length of detonating fuse to permit crimping on another blasting cap, and the perforator must be returned to the loading site for reloading before it is usable. This problem

2

occurs more frequently in the newly developed, small diameter, hollow carrier perforating apparatus which is adapted for running into a well through tubing previously set for permanent completion of the well. Chances of forming a sharp bend in the detonating fuse when the blasting cap is pushed up into the carrier is increased in this type of perforating apparatus because of the relatively narrow diameter of the carrier.

Therefore, it is an object of this invention to provide 10 a hollow carrier well perforating apparatus utilizing a fluid sensitive detonator assembly that can conveniently be placed in detonating relationship to a detonating fuse in the hollow carrier just prior to running the apparatus into the well.

An additional object of this invention is to provide 15 a hollow carrier well perforating apparatus incorporating a fluid sensitive electric detonator in which one leg wire of the detonator is conveniently grounded to the carrier.

A further object of this invention is to provide a fluid 20 sensitive detonating assembly that is adapted for use in small diameter, hollow carrier perforating apparatus.

A still further object of this invention is to provide a 25 fluid sensitive detonating assembly that does not require the crimping of a blasting cap to the detonating fuse.

Yet another object of this invention is to provide a 30 fluid sensitive detonating assembly wherein the assembly is positioned in detonating relationship to the detonating fuse, yet slidably movable along a length of the detonating fuse to prevent forming sharp bends and consequent misfire of the detonating fuse.

In general, the assembly of the present invention includes a liquid desensitized electric blasting cap having an elongated tubular case. The case contains a primary charge and a secondary charge which is longitudinally 35 separated from the primary charge by a flash chamber. Electrical energy means are provided to initiate the primary charge. Ports are provided in the case to admit liquid from the exterior into the flash chamber. The walls of the case surrounding the flash chamber further 40 provide a pair of diametrically opposed holes therethrough located closely adjacent to the secondary charge. The secondary charge is detonable by the primary charge when the flash chamber is dry and incapable of being detonated by the primary charge when the flash chamber contains 45 a liquid. A body is provided having substantially the same length as the secondary charge. The body provides a longitudinal bore therethrough adapted to receive the blasting cap with a close fit. The blasting cap is received in the bore of the body with the body surrounding substantially 50 only the portion of the case containing the secondary charge but with a small portion of the body overlying the pair of diametrically opposed holes in the case. The body provides a pair of holes therethrough registering with the pair of holes in the case. A length of 55 flexible wire extends through the registered holes in the case and the body securing the body to the case. The ends of the length of wire extend outwardly from the body and are adapted to provide means for slidably securing the assembly in the bottom of the tubular portion 60 of a hollow carrier shaped charge well perforating apparatus. The body further provides a fuse passage therethrough extending parallel to and intersecting the bore. The body, blasting cap and length of wire are adapted to slide along a detonating fuse inserted in the 65 passage. The body is adapted to position the portion of the fuse received in the passage in detonating relation to the secondary charge.

These and other objects, features and advantages of 70 the present invention will be apparent from a consideration of the following specification taken in conjunction with the accompanying drawing.

In the drawing:

FIG. 1 is a vertical view of a hollow carrier perforating apparatus with the lower end broken away to reveal the fluid sensitive detonating assembly;

FIG. 2 is an axial sectional view taken along line 2—2 in FIG. 3 of the fluid sensitive detonating assembly;

FIG. 3 is a plan view of the fluid sensitive detonating assembly;

FIG. 4 is an axial sectional view taken along line 4—4 in FIG. 5 of the retainer sleeve of the fluid sensitive detonating assembly; and

FIG. 5 is a plan view of the retainer sleeve of the fluid sensitive detonating assembly.

Referring to FIG. 1, a perforating apparatus is indicated generally by the numeral 10, the apparatus including an elongated, hollow cylindrical carrier 11, closed by a bull plug 12 at the lower end and a top closing member 13 at the upper end to provide a liquid-tight assembly. A cable head 14 is sealingly attached to the top closing member and retains the lower end of the suspending cable 15. An insulated electrical conductor wire 16 is provided in the core of the cable for connection to a source of electrical energy on the earth's surface. The steel sheath of the cable 15 and the metallic body of the perforating apparatus 10 furnish a return path for the electrical energy to the earth's surface.

The hollow carrier 11 is provided with a plurality of threaded port openings which are sealed by port plugs 17. Mounted in the hollow of the carrier, in axial alignment with the center of the port plugs, is a plurality of shaped charge units 18. The shaped charge units may be any of a number of commercially available units. A length of detonating fuse 19 extends throughout the length of the hollow carrier disposed in detonating relationship with each of the shaped charge units therein. The fluid sensitive detonating assembly, indicated generally by the numeral 20, is slidably attached to the length of detonating fuse 19 that extends below the lowermost shaped charge unit 18. The bull plug 12 provides a recess 21 in the upper end thereof which receives the lower portion of both the fluid sensitive detonating assembly and the detonating fuse.

The fluid sensitive detonating assembly 20 is illustrated in greater detail in FIG. 2 to which reference is now made. A tubular metal case 22 provides two sets of opposed ports or openings 23 therein to admit liquids from the exterior of the case into the flash chamber 24. The flash chamber is defined by the closed ends of the primary or initiation charge shell 25 and the secondary or detonator charge shell 26, and a section of the metal case 22 therebetween. The tubular case is preferably made of copper alloy and the primary and secondary charge shells are preferably made of aluminum alloy. The primary charge shell 25 is formed with a concavity 27 in the base and is tightly fitted in the case 22. A crimp 28 in the case 22 prevents the primary charge shell from moving into the flash chamber 24. The base end of the primary charge shell 25 is filled with a primary explosive charge 29, such as lead azide. Adjacent to the primary charge is the ignition charge 30 which contains an igniter wire 31 therein. The igniter wire is connected to extensions of the leg wires 32 which extend through the rubber seal plug 33 that closes the opening of the primary charge shell 25. A resistor 34 is connected in series with the igniter wire 31 by one of the extensions of leg wires 32. A bridge wire 35 is connected across the extensions of leg wires 32. Protection against accidental firing of the detonator is provided by the resistor 34 in series with the igniter wire 31, which increases the electrical energy required to fire the blasting cap. The bridge wire 35, in parallel with the series connected resistor and igniter wire, affords protection from accidental discharge of the blasting cap by electrostatic discharge. The leg wires project through a rubber seal plug 36 which is crimped

in the case 22 to provide a liquid-tight seal for the lower end of the case.

The detonator charge shell 26 has a lower half-section of slightly reduced diameter which is press fitted into the upper end of the case 22. Lowermost in shell 26 is a booster charge 37 of shock sensitive explosive such as lead azide. Above the booster charge is the secondary or detonating charge 38, which may be compressed pure Cyclonite or other suitable detonable explosive. The chamber 39, immediately above the detonator charge, is closed off with a cork stopper 40.

Slidably fitted over a portion of the outside of the case 22 is a detonating fuse retainer or sleeve 41. The sleeve is positioned substantially opposite that portion of the case 22 containing the booster charge 37 and secondary charge 38. As seen in FIGS. 4 and 5, the wall of the fuse retainer is provided with two transverse aligned openings 42 adjacent to one end. The openings 42 in the sleeve are adapted to register with the openings 23 in the case 22 which are adjacent to the secondary charge shell 26. A spring wire 43 inserted through the aligned openings in the case 22 and sleeve 41 retains the sleeve in a position opposite the detonating charge 38. This wire serves both to position the detonating assembly in the carrier and to provide a portion of the ground return of the firing circuit. The sleeve 41 should not extend any appreciable distance over the portion of the case 22 occupied by the flash chamber 24. If the sleeve extends substantially over the flash chamber, it will act as a reinforcement for the thin wall section of the case 22 and may cause a concentration upon the booster charge 37 of explosive energy from the detonation of the primary charge 29 sufficient to detonate the booster charge even when the flash chamber contains liquid. The external sections of the wire 43 are bent upward at their points of emergence from the case 22 at angles of approximately 45° to the case, and the terminal ends are bent inward toward the case. Other means for attaching the sleeve 41 to the case 22 may be used, such as a cotter pin or a short length of wire which may be inserted in the aligned openings and the projecting ends bent over against the case. It is necessary when using such other means to ground the return leg wire of the blasting cap as by connecting it electrically to the carrier.

Referring now to FIGS. 3, 4 and 5, the sleeve 41 provides a longitudinal bore 44 therethrough adapted to receive the case 22 in relatively close fit. A fuse passage 45 is provided in the sleeve, parallel to and intersecting the bore 44 of the sleeve. The diameter of the fuse passage is such that the sleeve 41 will slide freely over a length of Primacord received in the fuse passage, yet retain the Primacord in detonating relationship to the secondary charge 38. The sleeve 41 can be formed by crimping a strip of aluminum or copper around properly sized mandrels to produce openings 44 and 45. An alternative method of forming the sleeve is to crimp a proper length of aluminum or copper tubing around suitable mandrels to provide openings 44 and 45.

The fluid sensitive detonating assembly 20, as shown in FIG. 2, is conveniently assembled in the shop for distribution to the field. The leg wires 32 of the blasting cap provide shunting of the igniter wire 31, the bare ends of the leg wires being wrapped around the spring wire 43 to provide this result.

In operation, the fluid sensitive detonating assembly 20 is inserted in a previously loaded perforating apparatus 10, as shown in FIG. 1, just prior to running the apparatus into a well bore. The bull plug 12 is removed and either one of the leg wires 32 is unwrapped from the spring wire 43 and attached to the extension conductor wire 16a, which extends to the lower end of the carrier 11. The other leg wire 32 remains wrapped to spring wire 43 to provide a path for the ground return circuit for the blasting cap. Contact between spring wire 43, carrier 11 and the steel sheath of the conductor cable 15 provides

the ground return circuit to a source of electrical energy on the earth's surface. The end of detonating fuse 19 is inserted in the fuse passage in the sleeve of the detonating assembly 20. The ends of the spring wire 43 are flexed inwardly by hand and the assembly is slid along the detonating fuse past the internally threaded lower portion of the carrier, then released to engage the inside wall of the carrier. The detonator assembly is maintained centrally within the carrier by the spring wire and, in turn, retains the lower end of detonating fuse 19 centrally in the carrier. The bull plug 12 is screwed into the lower end of the carrier, receiving the detonating assembly 20 and the lower extremity of the detonator fuse 19 in the recess 21. Since no rigid attachment exists between the detonating assembly 20 and the detonating fuse 19, no kinks or sharp bends are formed in the detonating fuse as the detonating assembly is pushed up into the carrier.

The assembly of the present invention is also advantageously used in perforating apparatus that does not provide a recess in the bull plug to receive the detonating assembly. Screwing in the bull plug will force the detonating assembly to slide further up the Primacord with any sharp bends that may be formed being located below the point at which the Primacord is initiated by the detonating assembly.

The perforating apparatus is run into the well bore and positioned adjacent to the earth formation (not shown) to be perforated. Referring now to FIG. 2, upon application of electrical energy to the leg wires 32, the bridge wire 35 fuses, current flows through the igniter wire 31 which becomes incandescent, ignition charge 30 is initiated and, in turn, detonates primary charge 29. This detonation fragments the primary charge shell 25, with the concavity 27 producing a focusing effect to direct metal particles from the shell 25 into the base of shell 26. If no leaks have developed in the hollow carrier, the flash chamber 24 will not contain any liquids, and the particles of metal from shell 25 will strike the base of shell 26 with sufficient force to detonate the booster charge 37 and the secondary charge 38. If a leak does develop in the hollow carrier, the liquids collecting in the lower end of the carrier will enter through openings 23 in the detonating assembly and fill the flash chamber 24 with liquids. When the flash chamber contains liquids, the particles of metal from the shell 25 expend the greater part of their energy in traveling through the liquids and do not strike the base of shell 26 with sufficient force to detonate the booster charge and secondary charge. The unfired perforating apparatus must then be retrieved to the earth's surface, the source of leakage repaired, and a new detonator assembly 20 placed in the carrier. In the absence of liquid in the flash chamber, the booster charge 37 will detonate which detonates the secondary charge 38, in turn detonating the adjacent detonating fuse 19. The detonating fuse will then detonate the plurality of shaped charges 18, perforating the port plugs 17 and the earth formation.

While there has been described what is at present considered a preferred embodiment of the present invention, it will be apparent to those skilled in the art that various modifications and changes may be made without departing from the essence and scope of the present invention. In particular, it is contemplated that other types of fluid sensitive blasting caps may be used in the apparatus of the present invention. Therefore, the present invention is to be limited only by the scope and spirit of the appended claims.

We claim:

1. An assembly for firing a detonating fuse comprising: a liquid desensitized electric blasting cap having an elongated tubular case, a primary charge in said case, electrically energized means for initiating said primary charge, and a secondary charge in said case longitudinally separated from said primary charge by a flash chamber, said case providing ports for the admission of liquid from the exterior of said case into said flash chamber, the walls

of said case surrounding said flash chamber further providing a pair of diametrically opposed holes therethrough located closely adjacent to said secondary charge, said secondary charge being detonable by said primary charge 5 when said flash chamber is dry and incapable of being detonated by said primary charge when said flash chamber contains liquid; a body having substantially the same length as said secondary charge, said body providing a longitudinal bore therethrough adapted to receive said blasting cap with a close fit, said blasting cap being received in the bore of said body with said body surrounding substantially only the portion of said case containing said secondary charge but with a small portion of said body overlying said pair of diametrically opposed holes 10 in said case, said body providing a pair of holes therethrough registering with said pair of holes in said case; a length of flexible wire extending through the registered holes in said case and said body securing said body to said case, the ends of said length of wire extending outwardly from said body and adapted to provide means for slidably securing the assembly in the bottom of the tubular portion of a hollow carrier shaped charge well perforating apparatus; said body further providing a fuse passage therethrough extending parallel to and intersecting 15 said bore, said body, blasting cap and length of wire being adapted to slide along a detonating fuse inserted in said passage, and said body being adapted to position the portion of the fuse received in the passage in detonating relation to said secondary charge.

2. A well perforating apparatus comprising: an elongated, hollow, generally cylindrical, pressure resistant, sealed carrier adapted to be lowered into a well, said carrier providing an opening at the lower end thereof; removable means closing and sealing the opening in the 20 lower end of said carrier; at least one shaped charge unit positioned in the hollow of said carrier to direct the jet formed upon detonation through the side wall of said carrier; a cylindrical detonating fuse in the hollow of said carrier in detonating relationship to said shaped charge unit, the lower end of said fuse terminating within said carrier adjacent to the opening provided in the lower end of said carrier; an assembly for firing said detonating fuse, said assembly being adapted to pass through the opening at the lower end of said carrier, said assembly including 25 a liquid desensitized electric blasting cap having an elongated tubular case, a primary charge in said case, electrically energized means for initiating said primary charge, and a secondary charge in said case longitudinally separated from said primary charge by a flash chamber, said case providing ports for admission of liquid from the exterior of said case into said flash chamber, said secondary charge being detonable by said primary charge when said flash chamber is dry and incapable of being detonated by said primary charge when said flash chamber contains liquid, a detonating fuse retainer outside of and adjacent to said case, and means securing said retainer to said case, said retainer being positioned adjacent said case solely within a zone on said case extending from a location substantially opposite that end of said secondary charge which faces said flash chamber in a direction longitudinally away from said flash chamber, the thin wall section of said case defining said flash chamber being free from any reinforcement capable of causing sufficient concentration of explosive energy from the detonation of said primary charge to initiate detonation of said secondary charge when said flash chamber contains liquid, said retainer providing a longitudinal, cylindrical fuse passage therethrough parallel to and adjacent to said case and opposite said secondary charge, said fuse passage having a diameter which is greater than the diameter of said cylindrical detonating fuse whereby said lower end of said detonating fuse is loosely received in said passage to permit said retainer and blasting cap to slide 40 freely over the full length of said lower end of said detonating fuse.

3. The apparatus of claim 2, in which the longitudinal fuse passage is formed in the body of the carrier.

4. The apparatus of claim 2, in which the longitudinal fuse passage is formed in the body of the carrier.

5. The apparatus of claim 2, in which the longitudinal fuse passage is formed in the body of the carrier.

6. The apparatus of claim 2, in which the longitudinal fuse passage is formed in the body of the carrier.

7. The apparatus of claim 2, in which the longitudinal fuse passage is formed in the body of the carrier.

8. The apparatus of claim 2, in which the longitudinal fuse passage is formed in the body of the carrier.

9. The apparatus of claim 2, in which the longitudinal fuse passage is formed in the body of the carrier.

10. The apparatus of claim 2, in which the longitudinal fuse passage is formed in the body of the carrier.

11. The apparatus of claim 2, in which the longitudinal fuse passage is formed in the body of the carrier.

12. The apparatus of claim 2, in which the longitudinal fuse passage is formed in the body of the carrier.

13. The apparatus of claim 2, in which the longitudinal fuse passage is formed in the body of the carrier.

14. The apparatus of claim 2, in which the longitudinal fuse passage is formed in the body of the carrier.

15. The apparatus of claim 2, in which the longitudinal fuse passage is formed in the body of the carrier.

16. The apparatus of claim 2, in which the longitudinal fuse passage is formed in the body of the carrier.

17. The apparatus of claim 2, in which the longitudinal fuse passage is formed in the body of the carrier.

18. The apparatus of claim 2, in which the longitudinal fuse passage is formed in the body of the carrier.

19. The apparatus of claim 2, in which the longitudinal fuse passage is formed in the body of the carrier.

20. The apparatus of claim 2, in which the longitudinal fuse passage is formed in the body of the carrier.

21. The apparatus of claim 2, in which the longitudinal fuse passage is formed in the body of the carrier.

22. The apparatus of claim 2, in which the longitudinal fuse passage is formed in the body of the carrier.

23. The apparatus of claim 2, in which the longitudinal fuse passage is formed in the body of the carrier.

24. The apparatus of claim 2, in which the longitudinal fuse passage is formed in the body of the carrier.

25. The apparatus of claim 2, in which the longitudinal fuse passage is formed in the body of the carrier.

26. The apparatus of claim 2, in which the longitudinal fuse passage is formed in the body of the carrier.

27. The apparatus of claim 2, in which the longitudinal fuse passage is formed in the body of the carrier.

28. The apparatus of claim 2, in which the longitudinal fuse passage is formed in the body of the carrier.

29. The apparatus of claim 2, in which the longitudinal fuse passage is formed in the body of the carrier.

30. The apparatus of claim 2, in which the longitudinal fuse passage is formed in the body of the carrier.

31. The apparatus of claim 2, in which the longitudinal fuse passage is formed in the body of the carrier.

32. The apparatus of claim 2, in which the longitudinal fuse passage is formed in the body of the carrier.

33. The apparatus of claim 2, in which the longitudinal fuse passage is formed in the body of the carrier.

34. The apparatus of claim 2, in which the longitudinal fuse passage is formed in the body of the carrier.

35. The apparatus of claim 2, in which the longitudinal fuse passage is formed in the body of the carrier.

36. The apparatus of claim 2, in which the longitudinal fuse passage is formed in the body of the carrier.

37. The apparatus of claim 2, in which the longitudinal fuse passage is formed in the body of the carrier.

38. The apparatus of claim 2, in which the longitudinal fuse passage is formed in the body of the carrier.

39. The apparatus of claim 2, in which the longitudinal fuse passage is formed in the body of the carrier.

40. The apparatus of claim 2, in which the longitudinal fuse passage is formed in the body of the carrier.

41. The apparatus of claim 2, in which the longitudinal fuse passage is formed in the body of the carrier.

42. The apparatus of claim 2, in which the longitudinal fuse passage is formed in the body of the carrier.

43. The apparatus of claim 2, in which the longitudinal fuse passage is formed in the body of the carrier.

44. The apparatus of claim 2, in which the longitudinal fuse passage is formed in the body of the carrier.

45. The apparatus of claim 2, in which the longitudinal fuse passage is formed in the body of the carrier.

46. The apparatus of claim 2, in which the longitudinal fuse passage is formed in the body of the carrier.

47. The apparatus of claim 2, in which the longitudinal fuse passage is formed in the body of the carrier.

48. The apparatus of claim 2, in which the longitudinal fuse passage is formed in the body of the carrier.

49. The apparatus of claim 2, in which the longitudinal fuse passage is formed in the body of the carrier.

50. The apparatus of claim 2, in which the longitudinal fuse passage is formed in the body of the carrier.

51. The apparatus of claim 2, in which the longitudinal fuse passage is formed in the body of the carrier.

52. The apparatus of claim 2, in which the longitudinal fuse passage is formed in the body of the carrier.

53. The apparatus of claim 2, in which the longitudinal fuse passage is formed in the body of the carrier.

54. The apparatus of claim 2, in which the longitudinal fuse passage is formed in the body of the carrier.

55. The apparatus of claim 2, in which the longitudinal fuse passage is formed in the body of the carrier.

56. The apparatus of claim 2, in which the longitudinal fuse passage is formed in the body of the carrier.

57. The apparatus of claim 2, in which the longitudinal fuse passage is formed in the body of the carrier.

58. The apparatus of claim 2, in which the longitudinal fuse passage is formed in the body of the carrier.

59. The apparatus of claim 2, in which the longitudinal fuse passage is formed in the body of the carrier.

60. The apparatus of claim 2, in which the longitudinal fuse passage is formed in the body of the carrier.

61. The apparatus of claim 2, in which the longitudinal fuse passage is formed in the body of the carrier.

62. The apparatus of claim 2, in which the longitudinal fuse passage is formed in the body of the carrier.

63. The apparatus of claim 2, in which the longitudinal fuse passage is formed in the body of the carrier.

64. The apparatus of claim 2, in which the longitudinal fuse passage is formed in the body of the carrier.

65. The apparatus of claim 2, in which the longitudinal fuse passage is formed in the body of the carrier.

66. The apparatus of claim 2, in which the longitudinal fuse passage is formed in the body of the carrier.

67. The apparatus of claim 2, in which the longitudinal fuse passage is formed in the body of the carrier.

68. The apparatus of claim 2, in which the longitudinal fuse passage is formed in the body of the carrier.

69. The apparatus of claim 2, in which the longitudinal fuse passage is formed in the body of the carrier.

70. The apparatus of claim 2, in which the longitudinal fuse passage is formed in the body of the carrier.

71. The apparatus of claim 2, in which the longitudinal fuse passage is formed in the body of the carrier.

72. The apparatus of claim 2, in which the longitudinal fuse passage is formed in the body of the carrier.

73. The apparatus of claim 2, in which the longitudinal fuse passage is formed in the body of the carrier.

74. The apparatus of claim 2, in which the longitudinal fuse passage is formed in the body of the carrier.

75. The apparatus of claim 2, in which the longitudinal fuse passage is formed in the body of the carrier.

nating fuse to a position inside said lower end of said carrier while maintaining said lower end of said fuse in a substantially straight condition, and a portion of said detonating fuse within said fuse passage being in detonating relation to said secondary charge.

3. A well perforating apparatus comprising: an elongated, hollow, generally cylindrical, pressure resistant, sealed carrier adapted to be lowered into a well, said carrier providing an opening at the lower end thereof; removable means closing and sealing the opening in the lower end of said carrier; at least one shaped charge unit positioned in the hollow of said carrier to direct the jet formed upon detonation through the side wall of said carrier; a detonating fuse in the hollow of said carrier in detonating relationship to said shaped charge unit; an assembly for firing said detonating fuse, said assembly being adapted to pass through the opening at the lower end of said carrier, said assembly including a liquid densensitized electric blasting cap having an elongated tubular case, a primary charge in said case, electrically energized means for initiating said primary charge, and a secondary charge in said case longitudinally separated from said primary charge by a flash chamber, said case providing ports for admission of liquid from the exterior of said case into said flash chamber, the walls of said case surrounding said flash chamber further providing a pair of diametrically opposed holes therethrough located closely adjacent to said secondary charge, said secondary charge being detonable by said primary charge when said flash chamber is dry and incapable of being detonated by said primary charge when said flash chamber contains liquid, a body having substantially the same length as said secondary charge, said body providing a longitudinal bore therethrough adapted to receive said blasting cap with a close fit, said blasting cap being received in the bore of said body with said body surrounding substantially only the portion of said case containing said secondary charge but with a small portion of said body overlying said pair of diametrically opposed holes in said case, said body providing a pair of holes therethrough registering with said pair of holes in said case, and a length of flexible wire extending through the registered holes in said case and said body securing said body to said case, the ends of said length of wire extending outwardly from said body and slidably contacting the inner wall of said carrier to secure the assembly in the bottom of the tubular portion of said hollow carrier, said body further providing a fuse passage therethrough extending parallel to and intersecting said bore, said detonating fuse being slidably received in the bore of said body thereby permitting said body, blasting cap and length of wire to slide along said detonating fuse, said body positioning a portion of said fuse in detonating relationship to said secondary charge.

4. A well perforating apparatus as defined in claim 3 wherein said electrically energized means for initiating said primary charge includes a source of electrical energy having a grounded terminal; an igniter wire in said primary charge; a pair of leg wires connected to said igniter wire and extending externally of said tubular case; means electrically connecting one of said leg wires to said source of electrical energy; and means electrically connecting the other of said leg wires to said flexible length of wire; said hollow carrier being electrically conductive

and being grounded, and said length of flexible wire being electrically conductive and having its ends in electrical contact with the inner wall of said carrier at their points of slidable contact therewith.

5. A well perforating apparatus comprising: an elongated, hollow, generally cylindrical, pressure resistant, sealed carrier adapted to be lowered into a well, said carrier providing an opening at the lower end thereof; removable means closing and sealing the opening in the lower end of said carrier; at least one shaped charge unit positioned in the hollow of said carrier to direct the jet formed upon detonation through the side wall of said carrier; a detonating fuse in the hollow of said carrier in detonating relationship to said shaped charge unit, the lower end of said fuse terminating within said carrier adjacent to the opening provided in the lower end of said carrier; an assembly for firing said detonating fuse, said assembly being adapted to pass through the opening at the lower end of said carrier, said assembly including a liquid densensitized electric blasting cap having an elongated tubular case, a primary charge in said case, electrically energized means for initiating said primary charge, and a secondary charge in said case longitudinally separated from said primary charge by a flash chamber, said case providing ports for admission of liquid from the exterior of said case into said flash chamber, said secondary charge being detonable by said primary charge when said flash chamber is dry and incapable of being detonated by said primary charge when said flash chamber contains liquid, a detonating fuse retainer outside of and adjacent to said case, and means securing said retainer to said case solely within a zone on said case extending from a location substantially opposite that end of said secondary charge which faces said flash chamber in a direction longitudinally away from said flash chamber, said retainer providing a longitudinal fuse passage therethrough parallel to and adjacent to said case and opposite said secondary charge, said detonating fuse being slidably received in the fuse passage of said retainer with a portion of said fuse positioned in detonating relation to said secondary charge, oppositely disposed lengths of flexible wire fixed to said assembly and extending outwardly therefrom and slidably contacting the inner wall of said carrier, said means for initiating said primary charge having a source of electrical energy with a grounded terminal, an igniter wire in said primary charge, a pair of leg wires connected to said igniter wire and extending externally of said tubular case, means electrically connecting one of said leg wires to said source of electrical energy, means electrically connecting the other of said leg wires to one of said flexible lengths of wire, said one length of flexible wire being electrically conductive and having its end in electrical contact with the inner wall of said carrier at its point of slidable contact therewith, and said hollow carrier being electrically conductive and being grounded.
